UNITED STATES PATENT OFFICE

LOUIS C. WILKOFF, OF YOUNGSTOWN, OHIO, ASSIGNOR TO WILLIAM WILKOFF, INC., A CORPORATION OF OHIO

RAIL JOINT

Application filed January 5, 1929. Serial No. 330,646.

This invention relates to rail joints and more particularly to the improvement of splice bars wherein the clamping effect against the rail ends is improved, whether applied to new or worn rail ends, and aims generally to improve such joints and bars.

It is generally understood, in the art to which this invention relates that the maximum wear of the rail joint, due to the pounding action upon the rail ends by the rolling stock, is upon the under side of the rail head, and the adjacent upper contact edges of the splice bar. To compensate for this the bolts are taken up from time to time, to draw the splice bars upwardly toward the rails, which may, of course, be repeated until the splice bars engage the webs of the rails. When this occurs, further adjustment of the splice bars to compensate for such wear is not possible, and the bar is no longer useful for such wear.

Heretofore it has been proposed to reshape the worn splice bar to provide new contact surfaces for the worn portions of the rail ends by crowning or curving the upper contact edge of the bar, by a tolerated amount in excess of the normal fishing height of the bar, as disclosed for instance in the patent of E. Woodings No. 1,547,854, granted July 28, 1925. Such a bar is restricted in use to worn rail ends, and cannot readily be used with new rails without sacrificing much of the rail head support and resorting to an excessive amount of flexing of the ends of the bar inwardly.

My invention provides a new splice bar capable of use either with new or worn rails, and which will provide adequate support for the rail heads without resorting to excessive flexing of the bar.

Under present practice, using new rails of a given fishing height, there is in general a given fishing height of splice-bar for use therewith. The terms "normal fishing height for a rail" (or other terms of like import) used in my specification and claims, are intended to express shortly, the "fishing height of the ordinary splice-bars of uniform cross-section which would be used with the rail under consideration, when new, according to present practice." As rail sizes vary, the

only accurate way for me to generically define my invention is by a comparison with such a standard.

While my invention is applicable to many forms of splice-bar it is capable of being readily understood in its generic sense by reference to a single illustrative embodiment which I have shown in the accompanying drawings, wherein:

Fig. 1 is a side elevation of a rail joint illustrating the worn sections of the rail head and my improved splice bar applied thereto;

Fig. 2 is a transverse sectional view taken on the line $x-x$ of Fig. 1 showing the bar applied to a new or unworn rail joint;

Fig. 3 is a horizontal sectional view thereof taken on the line $3-3$ of Fig. 2;

Fig. 4 is a transverse sectional view taken on the line $x-x$ of Fig. 1 showing the splice bar applied to a worn rail joint;

Fig. 5 is a transverse sectional view thereof taken on the line $5-5$ of Fig. 4;

Fig. 6 is a transverse sectional view showing in full lines the position occupied by the new splice bar when applied to new or unworn rails, and in dotted lines as applied to worn rails, as compared with the position occupied by a splice bar of normal height as shown in dot and dash lines; and

Fig. 7 is a horizontal sectional view of another embodiment of my improved splice bar.

My invention may be embodied in the manufacture of new splice bars, as by rolling, or to reshaping splice bars, by any of the acceptable methods, and is adaptable to any of the standard types and shapes of bars as are commonly used in practice.

In practice the wear on the heads of the rails R , due to the pounding action of the rolling stock is at the joint and on the under side of the rail head, as indicated at 16 and is approximately one-sixteenth of an inch. In using splice bars of normal height only a portion of this wear can be compensated for by adjustment of the splice bars towards the web of the rails.

According to the present practice, reformed splice bars having an increased fishing height at the center, but normal fishing height at the ends, are inserted, so as to provide new con-

tact surfaces for the worn rails. However, such fish plates are not as adaptable for use when applied to new and unworn rails because the abnormal height of the bar materially cut down the bearing surface or fishing space of the bar against the under side of the rail head resulting in more rapid wear of the rails and bars.

My invention provides a new rail joint, and 10 a new splice bar, having the advantages of providing adequate fishing height for worn rails as well as adequate bearing surface or fishing space for new rails and hence is more universally adaptable for general use.

15 According to my invention, I increase the normal fishing height of the splice bar 10 uniformly throughout its length by a tolerated amount, usually less than the amount of wear on the under side of the rail heads, preferably 20 from one thirty-second to one-sixteenth of an inch or approximately one half of the tolerated wear on the under side of the rail heads. The opposed wearing surfaces of the bar are parallel so that when applied to 25 new rails (see Figs. 2 and 3) they will bear against the underside of the rail head 11 and the upper surfaces of the rail flanges 12 in planes parallel to the longitudinal axis of the rails. When applied to worn rails (see Figs. 30 4 and 5) the central portion of the bar may be drawn inwardly as indicated at 13 by the center bolts 14 so as to provide adequate bearing or rail clamping surface 15 and support for the worn portion 16 of the rails.

35 Thus my invention provides a splice bar capable of full fishing engagement when applied either to worn or unworn rails. In the former case (see Fig. 4) the fishing surface of the head of the bar is in full load 40 supporting engagement with the fishing surface of the rail head, particularly adjacent the joint where adequate support is needed. When applied to a new or unworn bar (see Fig. 2) the head of the bar is substantially in 45 full fishing engagement with the fishing surface of the rail head, having its major fishing surface in fishing engagement with the under side of the rail head.

Advantageously the splice bars may be 50 slightly cambered in a transverse plane as at 17 (Fig. 7) so as to relieve the center bolts 14 from strain when the bars are applied to worn rails. Such camber need only be slight, about one-eighth of an inch or less and is in a 55 direction so that the central portions of the splice bar normally will be closer to the web W of the rails than its ends. Thus when the bars are applied to worn rails they will not 60 be under undue tension and will not have a tendency to slip out of the fishing space. When applied to new rails, the end bolts 14 will be tightened to flex the ends of the bar 65 inwardly toward the web of the rails so that the bearing surfaces of the bar will be in

planes parallel to the longitudinal axis of the rails.

In Fig. 6 I have shown in dot and dash line 20 the position occupied by a new splice bar of normal fishing height, in full lines the position occupied by my improved bar when applied to new or unworn rails, and in dotted lines the position occupied by the new bar when applied to worn rails.

For purposes of illustration I have assumed a wear on the underside of the rail head of one-sixteenth of an inch, and according to my invention the height of the splice bar 10 is increased by approximately one half of such wear, or one-thirty-second of an inch in excess of the normal fishing height of the ordinary splice bar 20. The angles of inclination of the underside of the rail head and the rail flange are approximately 4 to 1 so that the new splice bar will be removed outwardly away from the normal fishing space by an amount approximately twice that the increase in fishing height of the bar, or in the illustrated arrangement, by one-sixteenth of an inch. Likewise, when my new bar is applied to a worn rail having a worn surface 16 of one-sixteenth of an inch, the center of the bar need only be drawn in towards the web approximately one-sixteenth of an inch as shown in dotted lines, Fig. 6, 95 beyond the normal fishing space indicated at 20, to provide new contact surfaces for the rail throughout the length of the bar.

It is only in exaggerated cases that the wear 16 on the rail head approaches one-sixteenth of an inch, and the average wear will probably range from one thirty-second of an inch to one-sixteenth. Hence, by increasing the normal fishing height of my bar by an amount less than the tolerated wear, it is obvious that my bar is more universally adaptable to a great variety of uses, as compared with the present practice of increasing the fishing height of the bar by one-sixteenth of an inch at the center only.

As is obvious from an inspection of Fig. 6, my improved bar clamps the rail head, of new rails, throughout a greater part of the normal fishing space than is possible with bars reclaimed according to the present practice above described, while at the same time providing for effectively clamping the rail heads of worn rails.

By increasing the fishing height of the splice bars uniformly throughout their length, as explained above, the bars are readily adaptable for use with new or unworn rails as they clamp the rail head throughout substantially the entire fishing space as illustrated in Fig. 6, wherein the normal fishing space is indicated in dot and dash lines and the portion thereof occupied by my new bar is shown in full lines. When applied to worn rails as shown in Figs. 1 and 4, the bar occupies a very substantial portion 120 125 130

of the normal fishing space because a portion of the wear to be compensated for is taken up by the increased fishing height of the bar and the remainder by flexing the central portion of the bar inwardly and upwardly.

My new splice bar, as explained above is equally adaptable to new or worn rails and in both instances provides adequate bearing surfaces for the rails thereby to prevent rapid wear of the rail heads at the joint. As the opposed wearing surfaces of the bars are parallel the bars may be rolled which is not possible with other bars having crowned wearing surfaces. With my new bars the cost of maintenance is materially reduced because of the longer life of the bar and the adaptability of adjustment to compensate for the wear of the rails as such wear takes place.

20 I claim:

1. A splice bar for use with worn or new rails having end and central rail clamping sections of uniform height in excess of the normal fishing height for said rails and being cambered transversely in a horizontal plane, and adapted when applied to new or unworn rail ends to provide rail clamping portions in planes substantially parallel to the vertical webs of the rails and when applied to worn rails to fit the fishing space closer to the rail webs at its central portion than at its ends.

2. A splice bar for use with worn or new rails having end and central rail clamping sections of uniform height in excess of the normal fishing height for said rails by approximately one thirty-second to one-sixteenth of an inch, and being cambered transversely in a horizontal plane and adapted when applied to new or unworn rail ends to provide rail clamping portions in planes substantially parallel to the vertical webs of the rails and when applied to worn rails to fit the fishing space closer to the rail webs at its central portion than at its ends.

3. A splice bar of uniform cross section throughout its length for use with new or worn rails, and having a fishing height in excess of the normal fishing height of said rails and clamping the fishing space from end to end, and being cambered transversely in a horizontal plane and adapted when applied to new or unworn rails to provide rail clamping portions in planes substantially parallel to the vertical webs of said rails and when applied to worn rails to have the central portion thereof positioned closer to the rail webs than the ends thereof to clamp the rails in the region of the worn out sections.

60 4. A splice bar of uniform cross section for use with new or worn rails, and having a fishing height in excess of the normal fishing height of said rails by approximately one-thirty-second of an inch and adapted when applied to new or unworn rails to provide

clamping portions from end to end and throughout substantially the entire normal fishing space in planes substantially parallel to the vertical webs thereof, and when applied to worn rails to clamp the entire normal fishing space in regions of the worn out sections of the rails.

5. A splice bar for use with new or worn rails having end and central rail clamping portions of uniform height in excess of the normal fishing height required for said rails when new, said bar having head and base flange fishing surfaces and adapted for fishing engagement with the heads of new rails, throughout the major portion of its head fishing surface in regions parallel to the web of the rail, and adapted for full fishing engagement with the heads of worn rails in regions closer to the web of the rail at the center of the bar than at the ends thereof.

In testimony whereof, I have signed my name to this specification.

LOUIS C. WILKOFF.
